CLIFFORD AUSTIN MEADOWS, OF TORONTO, ONTARIO, CANADA

METHOD OF MANUFACTURING SCREEN GUARDS AND SIMILAR DEVICES

Application filed September 15, 1927. Serial No. 219,731.

My invention relates to improvements in methods of manufacturing screen guards and similar devices, and the object of the invention is to devise a simple, cheap and rapid means of manufacturing screens of this type, and it consists essentially of the steps forming my method hereinafter described.

The drawing illustrates the various steps by which my method is carried out in which, 10 Fig. 1 represents a perspective view of a completed guard screen.

Fig. 2 is a sectional view through the flange bar out of which the frame is formed.

Fig. 3 is a view of a screen portion showing the edge upset vertically to fit the flange bar illustrated in Figure 2.

Fig. 4 is a similar view to Figure 2 showing the vertical flange of the flange bar bent inward at an incline ready for applying to 20 the screen body.

Fig. 5 is a sectional view through the flange bar showing it applied to the screen body in its initial position.

Fig. 6 is a similar view to Figure 5 showing the flange bar in the position it assumes 25 when it is applied to the screen body in the final position.

Fig. 7 is a plan view showing the method of jointing the angles of the frame.

30 Figs. 8 and 9 are similar views to Figures 5 and 6 and showing the final step clinching the screen body within the frame.

Fig. 10 is a front elevation of the parts shown in Figure 9. Fig. 11 is an alternative form of Figure 7.

In the drawing like characters of reference indicate corresponding parts in each figure.

In order to carry out my method the screen body 2 is upset upwardly as indicated at 2^x, 40 the portion 2^x extending at right angles to the body so as to fit the interior angle of the bar 1. The flange bars 1 of the form shown in Figure 2 have the vertical flanges 1^x of the bar 1 greater in proportion to the horizontal flange 1°. 45 The upper portion of the vertical flange 1^x

of the flange bar 1 is then bent inwardly to an angular position as indicated at 3 in Figure 4. When each of the bars 1 forming the sides of the frame have been bent into this form they are cut into lengths and then applied to each of the upset edges 2^x of the screen body 2 by hooking the portion 3 over the portion 2^x into the position shown in Figure 5 and then swinging the bar inwardly so that the portion 1^x, see Figure 5, is carried to a vertical position as indicated in Figure 6, against the upset edge 2^x of the frame 2, the horizontal flange 1° of the flange bar then resting against the bottom of the screen body.

When each of the flange bar sections forming the sides of the frame have been applied to the screen body to assume the position in Figure 6, the horizontal flanges 1° of the adjacent bar portions overlap one over the other as indicated in Figure 7 or are mitred as in Figure 11. These overlapping portions may be then riveted together by a connecting rivet 4. After this has been done the ends of the flange portions 3 are manually pinched inwardly by a suitable tool against the inner face of the upset edges 2^x of the screen body so as to retain the bars 1 in position around the screen body. The ends of the bars are then welded or otherwise suitably connected together and the body of the flange portion 3 between the pinched in portions 4^x are pressed inwardly so as to grip the upwardly extending edge portions 2^x of the screen body as illustrated in Figures 8, 9 and 10 thereby completing the screen.

By this method the screen is formed very rapidly with a minimum expenditure of time and labour and therefore greatly cheapening the cost of manufacture.

What I claim as my invention is:—

1. A method of manufacturing screen guards and the like consisting of up-turning the edges of the screen body to an angular position, bending a flange of a flanged bar inwardly on a medial longitudinal line to

form an acute angle, then cutting the bar into sections to form the sides of the screen frame, hooking such angularly bent portion over the up-turned edges of the screen body, swinging the bars inwardly so that the base portion of such flange and the flange extending at right angles thereto fit against the up-turned portion of the body and the face of the screen body adjacent thereto, securing the ends of the bar sections together and forcing the inclined portions of the bar flanges inwardly against the vertical portion to grip the up-turned screen edges therebetween.

2. A method of manufacturing screen guards and the like consisting of up-turning the screen body to an angular position, bending the vertical flange of a flanged bar inwardly on a medial longitudinal line to form an acute angle, cutting the flanged bar into sections to form the sides of the screen frame, hooking such angularly bent portions over the up-turned edges of the screen body, successively swinging the bars inwardly so that the vertical and horizontal flanges fit against the vertical and horizontal portions of the screen body, pinching the ends of the inclined portions of each flanged bar flange inwardly as it is brought into position against the screen body, securing the ends of the bars together, and forcing the inclined portions of the flange of the flanged bar sections inwardly against the vertical portion of the flange to grip the up-turned edges therebetween.

3. A method of manufacturing screen guards and the like consisting of up-turning an edge of a screen body to an angular position, taking a bar having flanges extending at an angle one to the other, bending one of the flanges of the flanged bar inwardly on a medial line to form an acute angle, applying the flanged bar to a screen body by hooking such angularly bent portion over the up-turned edge of the body, swinging the bar inwardly against the up-turned edge and beneath the body, and forcing the angularly in-bent portion of the flanged bar inwardly towards the body of the flange to grip the up-turned edge therebetween.

4. A method of manufacturing screen guards and the like consisting of up-turning the edges of the screen body to an angular position, bending bars on their medial longitudinal line and applying the bars to the sides of the up-turned portions of the screen so that such up-turned portions extend between the bent portions of the bars, securing the adjacent ends of the bars together and forcing the bent portions of the bars towards the other side of the up-turned portions of the screen to grip such up-turned portions between the two opposing portions of the bar.

5. In the method of manufacturing screen guards and the like, up-turning the edges of a screen body to an angular position, bending a bar on its medial longitudinal line to a

point intermediate between its normal and final positions and applying the bar to one side of the up-turned portion of the screen so that such up-turned portion extends between the bent portions of the bar, and finally forcing the bent portion of the bar from its intermediate positions towards the other unbent portion of the bar and against the other side of the up-turned portion of the screen to grip such up-turned portion between the two portions of the bar.
